9 Claims. (Cl. 260—668)

This invention relates to a process for the production 10 of aromatic hydrocarbons and more particularly to the production of p-xylene.

Processes for reforming petroleum hydrocarbons boiling in the gasoline boiling range have greatly increased the quantity of aromatic hydrocarbons produced in the 15 refining of petroleum fractions. Among the aromatic hydrocarbons produced from petroleum fractions are the xylene isomers which are usually present in approximately the equilibrium ratio of about 2 parts of o-xylene, 2 parts p-xylene and 5 parts m-xylene. In spite of the 20 greatly increased supply of aromatic hydrocarbons resulting from reforming operations, the demand for p-xylene has increased to such an extent that it is desirable to increase the yield of p-xylene from petroleum fractions still further.

In the process usually employed for the recovery of pure xylene isomers, o-xylene is separated from the m- and p-xlyenes by a precision distillation; however, the boiling points of m- and p-xlyenes are too close to allow separation by distillation. The resulting mixture of m- and p-xlyenes is fractionally crystallized to separate crystals of substantially pure p-xylene. A low melting point 25 eutectic mixture of m- and p-xlyenes containing about 12 percent p-xylene prevents recovery of all of the p-xylene by crystallization. The mother liquor, which is rich in m-xylene, obtained from the crystallization can be isomerized to convert part of the m-xylene to p-xylene, but the isomerization of m-xylene yields a reaction product having at best the equilibrium ratio of p- to m-xylene.

In this invention, naphthenic compounds containing 8 carbon atoms per molecule are isomerized to give a p-xylene precursor in concentrations higher than the concentration of p-xylene in an equilibrium mixture of xlyenes, and the p-xylene precursor is dehydrogenated to form p-xylene. The p-xylene thus formed can be separated from other compounds present in the dehydrogenated product by conventional methods such as those described in the preceding paragraph. In a preferred embodiment of the process a charge stock consisting principally of m-xylene is hydrogenated to dimethylcyclohexane and the dimethylcyclohexane isomerized. An especially high yield of p-xylene can be obtained if the isomerized is fractionally distilled in a precision distillation to form an overhead product consisting of a mixture of trans-1,4 dimethylcyclohexane, cis-1,3 dimethylcyclohexane and 1,1 dimethylcyclohexane as an overhead product. The overhead product from the distillation is then dehydrogenated to yield p-xylene which is separated from other xylene isomers.

The single FIGURE in the drawing is a diagrammatic representation of the procedural steps employed in a preferred embodiment of this invention.

The feed stock for the process of this invention can be any hydrocarbon fraction which includes cyclic hydrocarbons having 8 carbon atoms per molecule. For example, a feed stock for a reforming operation such as a platformer feed stock can be used. If the feed stock contains naphthenic and paraffinic hydrocarbons, those compounds will be substantially unaffected in the hydrogenation step, which is for converting xylenes to dimethylcyclohexanes. In general, it is desirable to have low

2

concentrations of aromatic hydrocarbons in the isomerization charge stock to reduce the consumption of isomerization catalyst and the sludge formation in the isomerization step.

A preferred charge stock is a mixture of C-8 aromatic hydrocarbons which may be obtained from a reforming process, for example, Platforming, combined with processes such as Udex or Arosorb processes for the recovery of the aromatic hydrocarbons. The Platforming, Udex and Arosorb processes are well known commercial processes. Since the primary object of this invention is the production of p-xylene for recovery of that isomer substantially free of other xylene isomers, apparatus for separating p-xylene from m-xylene ordinarily would be available at a plant or refinery using this invention. Hence, a stream of m-xylene from which the o-xylene has been removed by fractional distillation and p-xylene has been removed by fractional crystallization is an especially desirable feed stock. The m-xylene will ordinarily contain about 12 percent p-xylene and may also contain ethylbenzene. Ortho-xylene can also be used as a charge stock.

The hydrogenation step is only sufficiently severe to convert aromatic hydrocarbons to naphthenic hydrocarbons; hence, it may easily be carried to substantial completion. Many of the well known catalysts used in conventional hydrocarbon hydrogenation processes can be employed at hydrogenation conditions. Raney nickel is a preferred hydrogenation catalyst and can be employed at mild conditions such as at temperatures of 200° C. and a pressure of 1500 pounds per square inch. Examples of other catalysts which can be employed are nickel, copper chromite, nickel oxide, molybdenum sulfide, tungsten sulfide, cobalt molybdate and chromia, either alone or supported on a suitable carrier such as alumina. The temperature, pressure and time used in the hydrogenation are interdependent and also depend upon the hydrogenation catalyst used. In general, the temperature will be in the range of 90° C. to 375° C., the pressure will be 500 pounds per square inch, or higher, and the time less than about 3 hours.

At the mild hydrogenation conditions employed, isomerization of the feed stock will ordinarily be slight, and, particularly when the feed stock is predominantly m-xylene, any isomerization that does occur may be beneficial. The ease with which the aromatic hydrocarbons can be hydrogenated will cause the concentration of the aromatic hydrocarbons in the hydrogenated product to be small in most instances. However, it may be desirable to strip the xylenes or other aromatic hydrocarbons from the hydrogenated material prior to the isomerization step. The aromatic hydrocarbons can be stripped by the use of selective solvents or by passing the hydrogenated hydrocarbons over silica gel.

The naphthenic hydrocarbons from the hydrogenation step are isomerized, preferably at a low temperature in the presence of a highly active isomerization catalyst. A low temperature, below about 150° C., and preferably between about 30° C. and 90° C., favors an equilibrium in which the concentration of 1,4 dimethylcyclohexanes is high and there is a high ratio of trans-1,4 dimethylcyclohexane to cis-1,4 dimethylcyclohexane. The high ratio of trans-1,4 dimethylcyclohexane to cis-1,4 dimethylcyclohexane is of value in increasing the concentration of p-xylene precursors in the manner to be described. The isomerization is preferably carried out in the presence of an aluminum chloride catalyst in concentrations of about 1 to 30 percent, which allows reaction times as short as one hour with satisfactory yields of p-xylene precursors and reaction times as short as about 3 hours for a substantially complete isomerization to an equilibrium com-

position of dimethylcyclohexanes. A low temperature is especially valuable in reducing sludge formation in isomerization in the presence of aluminum chloride. Other catalysts, such as hydrogen fluoride and boron trifluoride, can also be employed; however, those catalysts require higher temperatures with resultant less favorable equilibrium compositions and longer reaction times.

The isomerization product, designated as the isomerizate, contains the following mixture of isomers of dimethylcyclohexane.

Isomer of dimethylcyclohexane:	Boiling point, °C.
Trans-1,4	119.35
1,1	119.54
Cis-1,3	120.09
Trans-1,2	123.42
Cis-1,4	124.32
Trans-1,3	124.45
Cis-1,2	129.73

The ratio of trans-1,4 dimethylcyclohexane to cis-1,4 dimethylcyclohexane in the isomerizate is substantially higher than the ratio of cis-1,3 dimethylcyclohexane to trans-1,3 dimethylcyclohexane. The approximately 3.3° C. difference in the boiling point of the cis-1,3 dimethylcyclohexane and trans-1,2 dimethylcyclohexane permits an efficient separation to be made between the first three isomers listed and the last four in a precision distillation such as can be obtained, for example, in a 70 plate Stedman column. This fractionation produces an overhead product having a high, and a bottoms product having a low, concentration of 1,4 dimethylcyclohexanes. If desired, the distillation can be made to leave a portion of the cis-1,3 dimethylcyclohexane in the bottoms product, or a more efficient distillation can be used, to increase the concentration of trans-1,4 dimethylcyclohexane in the overhead product.

Either the total isomerizate, or the overhead product from the distillation of the isomerizate if a distillation step is employed, is dehydrogenated in a conventional dehydrogenation process at conditions to avoid isomerization of the resulting aromatic hydrocarbons. The dehydrogenation can be accomplished, for example, in the presence of a noble metal, such as platinum or palladium, dehydrogenation catalyst. A preferred dehydrogenation catalyst is platinum, which may be deposited on a support. Suitable supports are alumina, silica, and deactivated silica-alumina. If a platinum dehydrogenation catalyst is used, the isomerizate can be dehydrogenated at temperatures of about 250° to 400° C., for example, about 325° C.

Other well known dehydrogenation catalysts such as chromium oxide supported on alumina are suitable for the dehydrogenation, but require temperatures in the range of about 500° to 600° C. Molybdena, preferably supported on alumina, and cobalt molybdate can also be used. The dehydrogenation is preferably accomplished at low pressures such as atmospheric pressure.

The invention may be more clearly understood by reference to the attached drawing in which preferred embodiments of the process for the production of p-xylene from m-xylene are illustrated diagrammatically. The m-xylene charge stock is introduced through a feed line 10 to a hydrogenated step 12, in which the m-xylene is substantially completely hydrogenated to form 1,3 dimethylcyclohexanes. Hydrogen for the hydrogenation is introduced through a supply line 14 which joins feed line 10.

The dimethylcyclohexanes are delivered from the hydrogenation step 12 through a line 16 to an aromatic hydrocarbons removal step 18. Ordinarily the aromatic hydrocarbons are substantially completely hydrogenated; hence, the quantity that must be removed in step 18 will be small, for example, about one percent or less of the total hydrogenated product. The aromatic hydrocarbons removed in step 18 are preferably recycled through a line 20 to the feed line 10. If desired, the aromatic hydro-

carbons stripped from the hydrogenated product in step 18 can be removed from the system through line 22.

The substantially aromatic-hydrocarbon-free dimethylcyclohexanes are delivered from aromatic-hydrocarbons removal step 18 through line 24 to an isomerization step 26. The isomerizate from step 26 is delivered through a line 28 to a precision distillation step 30 in which the 1,1 dimethylcyclohexane, trans-1,4 dimethylcyclohexane and cis-1,3 dimethylcyclohexane are removed as an overhead product, and delivered through a line 32 to a dehydrogenation step 34. The bottoms product from the distillation step 30, consisting of cis-1,4 dimethylcyclohexane, trans-1,3 dimethylcyclohexane, cis-1,2 dimethylcyclohexane and trans-1,2 dimethylcyclohexane, can be recycled through line 36 to line 24 for another pass through the isomerization step 26 or discharged from the system through a line 38.

The dehydrogenation step 34 is accomplished at conventional dehydrogenation conditions to convert the dimethylcyclohexanes to xylenes. Hydrogen liberated from step 34 is recycled through a line 40 to the hydrogenation step 12.

The xylenes produced in the dehydrogenation step 34 are delivered through a line 42 to a fractional crystallization process 44 for the separation of m- and p-xylene. The isomerization of the naphthenic compounds combined with the precision distillation allows the production of a xylene stream having a concentration of approximately 35 percent p-xylene. m-Xylene separated from the p-xylene in the fractional crystallization is recycled through a line 46 for additional passes through the process.

The following examples illustrate the improved yield of p-xylene made possible by this invention.

EXAMPLE I

A charge stock of a hydrocarbon fraction containing 2.1 percent ethylbenzene, 1.1 percent o-xylene, 1.6 percent p-xylene and the remainder m-xylene, mixed with 40 30 percent of its weight of aluminum chloride, was agitated at a temperature of 55° C. for a period of 2 hours. The aluminum chloride and reaction products were separated and the reaction products analyzed to determine the concentration of the individual hydrocarbon compounds.

EXAMPLE II

A sample of the charge stock employed in Example I admixed with 30 percent of its weight aluminum chloride 50 was agitated at a temperature of 85° C. for a period of 2 hours. The reaction product was separated from the aluminum chloride and analyzed.

EXAMPLE III

55 A sample of the charge stock of Example I was mixed with 30 percent of its weight of aluminum chloride and agitated at a temperature of 85° C. for 4 hours. The reaction product was separated from the aluminum chloride and analyzed.

EXAMPLE IV

A sample of the charge stock employed in Example I was hydrogenated at 309° F. and 1500 pounds per square inch gauge in the presence of 10 percent by weight of 65 Raney nickel. Approximately 0.5 percent of the m-xylene was not converted to naphthenes and was removed from the reaction products by treatment with silica gel. The dimethylcyclohexanes formed by the hydrogenation were mixed with 30 percent of their weight of aluminum chloride and agitated at a temperature of 65° C. for a period of 3 hours. A sample of the reaction products was analyzed to determine the concentration of each of the isomers of dimethylcyclohexane. A separate sample of the isomerizate was dehydrogenated 70 at 325° C. by passing it over platinum on activated car-

bon at a liquid hourly space velocity of 0.16. A conversion of the naphthenes of 96-97 percent was obtained without appreciable isomerization. The dehydrogenated reaction product was analyzed to determine the concentration of individual xylene isomers and ethyl benzene.

EXAMPLE V

A sample of the charge stock employed in Example I was treated in the manner described for Example IV with the exception that a small amount of arsenious chloride was added to the aluminum chloride.

EXAMPLE VI

A sample of the charge stock employed in Example I was treated in the manner described for Example IV with the exception that a small amount of formaldehyde was added to the aluminum chloride isomerization catalyst.

EXAMPLE VII

A sample of the charge stock employed in Example I was treated in the manner described for Example IV with the exception that the naphthene fraction was agitated with the aluminum chloride isomerization catalyst for a period of 6½ hours.

EXAMPLE VIII

A sample of a charge stock employed in the other examples was hydrogenated in the manner described for Example IV and isomerized at the conditions described for Example IV. The isomerize was distilled in a precision fractionating column to separate cis-1,3 dimethylcyclohexane, trans-1,4 dimethylcyclohexane and 1,1 dimethylcyclohexane as an overhead product. A sample of the overhead product was analyzed to determine the proportions of the different naphthene isomers. The overhead product was dehydrogenated in the presence of a platinum dehydrogenation catalyst in the manner described for Example IV.

EXAMPLE IX

A sample of the charge stock employed in Example I was treated in the manner described for Example VIII with the exception that following the isomerization reaction in the presence of aluminum chloride, the reaction product was refluxed for 16 hours at a temperature of 119° C. in the presence of a trace of aluminum chloride.

The results of the experimental runs are set forth in Table I.

Table I

Charge Stock	Example No.

¹ Refluxed at 120° C. for 16 hours after reaction period.

² Promoted with AsCl₃.

³ Promoted with HgCl₂.

It will be seen from Table I that the hydrogenation of the m-xylene to dimethylcyclohexanes prior to isomerization allows the concentration of the 1,4 isomer in the isomerize to be increased to approximately 26 percent from the 22 percent obtained upon the isomerization of m-xylene. When a preferred feed stock, the mother liquor from a fractional crystallization process for the separation of m- and p-xylanes, is employed, direct isomerization of m-xylene to p-xylene only gives a net gain of about 10 percent p-xylene. The hydrogenation of m-xylene prior to isomerization allows a net gain in p-xylene of about 14 percent. When the naphthene isomerize is fractionally distilled prior to dehydrogenation, as in Examples VIII and IX, an increase of about 22 percent in the concentration of p-xylene is obtained. Even higher gains are possible with more efficient fractionation and alteration of the cut point to leave a portion of the cis-1,3 dimethylcyclohexane in the bottoms product.

We claim:

1. A process for the production of p-xylene comprising hydrogenating m-xylene to form dimethylcyclohexanes, contacting the dimethylcyclohexanes with aluminum chloride at a temperature in the range of about 30° to 150° C. to form an isomerize containing a high concentration of 1,4 dimethylcyclohexanes, and dehydrogenating the isomerize to the corresponding isomers of xylene.
2. A process for the production of a mixture of C₈ aromatic hydrocarbons having a p-xylene concentration higher than the concentration of p-xylene in an equilibrium mixture of the C₈ aromatic hydrocarbons comprising contacting dimethylcyclohexane with aluminum chloride at a temperature in the range of 30° to 150° C. to form an isomerize having a high concentration of 1,4 dimethylcyclohexanes, then contacting the isomerize with a dehydrogenation catalyst to convert 1,4 dimethylcyclohexanes to p-xylene, the contact of the dimethylcyclohexanes and dehydrogenation catalyst being at conditions to avoid substantial isomerization of the p-xylene.
3. A process as set forth in claim 2 in which the dehydrogenation catalyst is a platinum catalyst and the temperature at which the isomerize is contacted with the dehydrogenation catalyst is in the range of 250° to 400° C.
4. A process for the production of a mixture of C₈ aromatic hydrocarbons having a p-xylene concentration higher than the concentration of p-xylene in an equilibrium mixture of the C₈ aromatic hydrocarbons comprising contacting 1,3 dimethylcyclohexanes with aluminum chloride at a temperature in the range of about 30 to 150° C. to

form an isomerize containing a high concentration of 1,4 dimethylcyclohexanes, separating the isomerize from the aluminum chloride, distilling the thus separated isomerize to form an overhead product consisting principally of trans-1,4 dimethylcyclohexane and cis-1,3 dimethylcyclohexane in a precision distillation, and passing the overhead product in contact with a dehydrogenation catalyst at conditions to convert 1,4 dimethylcyclohexanes to p-xylene and to avoid substantial isomerization of the p-xylene.

5. A process for the preparation of a mixture of C_8 aromatic hydrocarbons having a p-xylene concentration higher than the concentration of p-xylene in an equilibrium mixture of the C_8 aromatic hydrocarbons comprising contacting dimethylcyclohexane with an active isomerization catalyst at a low temperature to form an isomerize containing a high concentration of 1,4 dimethylcyclohexanes, separating the isomerize from the isomerization catalyst, distilling the isomerize to separate an overhead product consisting principally of trans-1,4 dimethylcyclohexane and cis-1,3 dimethylcyclohexane from trans-1,3 dimethylcyclohexane and cis-1,4 dimethylcyclohexane, recycling the bottoms product from the distillation through the isomerization step, and dehydrogenating the overhead product to convert trans-1,4 dimethylcyclohexane to p-xylene.

6. A process for the production of p-xylene comprising passing a mixture of m-xylene and hydrogen in contact with Raney nickel at a temperature of about 200° C. and a pressure of about 1500 pounds per square inch to convert m-xylene to dimethylcyclohexanes, contacting the dimethylcyclohexanes with aluminum chloride at a temperature in the range of about 30° to 150° C. to form an isomerize containing a high concentration of 1,4 dimethylcyclohexanes, and passing the 1,4 dimethylcyclohexanes in contact with platinum supported on activated carbon at a temperature of about 325° C. to dehydrogenate the 1,4 dimethylcyclohexanes and thereby form p-xylene.

7. A process for the production of p-xylene from an isomer of xylene other than p-xylene comprising hydrogenating said isomer to form dimethylcyclohexane, then contacting the thus formed dimethylcyclohexane with an isomerization catalyst to form a mixture of isomers of dimethylcyclohexane having a concentration of 1,4-dimethylcyclohexane higher than the concentration of p-xylene in an equilibrium mixture of xylenes, distilling the mixture of isomers of dimethylcyclohexane to separate an overhead product consisting principally of trans-1,4-dimethylcyclohexane and cis-1,3-dimethylcyclohexane from cis-1,4-dimethylcyclohexane and trans-1,3-dimethyl-

cyclohexane, and passing the overhead product in contact with a dehydrogenation catalyst at conditions to convert 1,4-dimethylcyclohexane in said overhead product to p-xylene.

5 8. A process for the production of p-xylene from an isomer of xylene other than p-xylene comprising hydrogenating said isomer to form dimethylcyclohexane, then contacting the dimethylcyclohexane with an isomerization catalyst at a temperature below about 150° C. to form a mixture of isomers of dimethylcyclohexane, distilling the mixture of isomers of dimethylcyclohexane to separate an overhead product consisting principally of trans-1,4-dimethylcyclohexane and cis-1,3-dimethylcyclohexane, from cis-1,4-dimethylcyclohexane and trans-1,3-dimethylcyclohexane, and passing the overhead product in contact with a dehydrogenation catalyst at conditions to convert 1,4-dimethylcyclohexane in said overhead product to p-xylene.

9. A process for the production of p-xylene from an isomer of xylene other than p-xylene comprising hydrogenating said isomer to form dimethylcyclohexane, contacting the thus formed dimethylcyclohexane with aluminum chloride at a temperature below about 150° C. to form an isomerize containing 1,4-dimethylcyclohexane, and dehydrogenating the isomerize at conditions whereby the 1,4-dimethylcyclohexane is dehydrogenated to p-xylene.
